UNITED STATES PATENT OFFICE.

MARION M. MCCOY, OF DAWSON, NEW MEXICO, ASSIGNOR OF ONE-HALF TO G. A. WILL,
OF ST. LOUIS, MISSOURI.

INTERNAL-COMBUSTION ENGINE.

1,269,195.

Specification of Letters Patent. Patented June 11, 1918.

Application filed November 27, 1916. Serial No. 133,751.

To all whom it may concern:

Be it known that I, MARION M. McCoy, a citizen of the United States, residing at Dawson, county of Colfax and State of New Mexico, have invented a certain new and useful Improvement in Internal-Combustion Engines, of which the following is a full, clear, and exact description, such as will enable others skilled in the art to which it appertains to make and use the same, reference being had to the accompanying drawings, forming part of this specification.

My invention relates to internal combustion engines, the principal object of my invention being to generally improve upon and simplify the existing types of internal combustion engines and further to provide an engine having a comparatively high degree of efficiency.

Further objects of my invention are to provide an engine having twin cylinders and a double headed piston operating in each cylinder with both pistons connected to the crank shaft by single pitman or connecting rod, and further to provide means for the introduction, compression and the firing of explosive vapor in both ends of each cylinder.

With the foregoing and other objects in view, my invention consists in certain novel features of construction and arrangement of parts, hereinafter more fully described and claimed, and illustrated in the accompanying drawings, in which—

Figure 1 is a vertical section taken through the center of an internal combustion engine of my improved construction.

Fig. 2 is a diagrammatic view illustrating the positions of the valves during the various strokes of the piston.

Fig. 3 is a vertical section taken approximately on the line 3—3 of Fig. 1.

Fig. 4 is a horizontal section taken approximately on the line 4—4 of Fig. 1.

Fig. 5 is an elevational view of the engine with the cam shaft housing in section.

In the drawings which illustrate a practical embodiment of my invention, 10—10 designate twin cylinders which are arranged side by side and each cylinder being provided with the usual combustion chamber 11 in which operates a double headed piston 12. The central portions of the two pistons are connected by a wrist-pin 13, the same extending through vertically disposed

slots 14 formed in the walls of the cylinders 10 and mounted on the central portion of this wrist-pin is the upper end of a pitman or connecting rod 15, the lower end of which is connected in the usual manner to 60 a crank shaft 16. This crank shaft is journaled in suitable bearings in the end walls of a crank case 17, the latter being provided with a top plate 18, the same serving as heads for the lower ends of the combustion chambers 11. The upper ends of these combustion chambers are closed by a head or plate 19, the same being secured to the cylinders 10 in any suitable manner.

Necessarily, the central portion of plate 70 18 is provided with an opening 20 through which the pitman 15 operates.

The walls of the cylinders 10 and plates 75 18 and 19 are preferably provided with communicating chambers or spaces through which cooling fluid may circulate, said fluid entering the chamber in plate 18 through a pipe 21 and discharging through a pipe 22 which leads from the chamber within plate 19.

Each end of each cylinder 10 is provided with an extension 23 and formed in each extension is an ignition chamber 24 and with inlet and exhaust chambers 25 and 26 respectively, the latter lying side by side and 85 located immediately adjacent to the corresponding ignition chamber.

Suitable openings are formed through the wall separating the chambers 25 and 26 from the chamber 24, and normally closing 80 said openings are inlet and exhaust valves 27 and 28 respectively.

Secured to each valve is a stem or operating rod 29 and all of said stems or rods are arranged for sliding movement through 95 suitable bearings 30 seated in the extension 23.

Positioned on each rod is a compression spring 31, the same being arranged to maintain the valve in closed position upon its 100 stem. The stems or rods of the valves at the upper ends of the cylinders project downwardly, while the stems or rods of the valves at the lower ends of the cylinders project upwardly and the adjacent ends of 105 all of the valve stems terminate within cam shaft housings 32, which latter are fixed to the engine cylinders in any suitable manner.

Operating in suitable bearings formed on 110

the ends of these housings 32 is a cam shaft 33 and formed integral therewith or fixed thereto are cams 34, the same being arranged so as to bear directly against the inner ends of the valve stems or rods 29.

Fixed on one end of the cam shaft 30 is a sprocket wheel 35 and operating thereupon is a sprocket chain 36 which passes around a sprocket wheel 37 that is carried by a crank shaft 16. The sizes of the sprocket wheels 35 and 37 are such that the cam shaft makes one revolution for each two revolutions of the crank shaft.

Fixed to each extension 23 is a manifold 38, the same being provided with an intake 15 38, the same being provided with an intake chamber 39 and leading therefrom to the inlet valve chambers 25 are ports 40. Each manifold 38 is provided with an exhaust chamber 41 and leading therefrom to the 20 exhaust valve chambers 26 are ports 42.

Ordinary spark plugs such as 43 are seated in the walls of the engine cylinders with the points of said plugs positioned in the ignition chambers 24.

25 The operation of my improved engine is as follows:

By referring to diagram A of Fig. 2, it will be noted that as the piston 12 moves downward on one of its strokes, the inlet 30 valve at the upper end of the cylinder is open and the exhaust valve at the lower end of said cylinder is also open, said valves being thus positioned by the corresponding cams on shaft 33, with the result that a charge of explosive vapor is drawn into the chamber 11 above the piston and simultaneously the burnt gases produced by the firing of the charge previously drawn into the lower portion of the chamber are forced 35 outward through the opening exhaust valve at the lower end of the cylinder. While this stroke takes place, the exhaust valve at the upper end of the cylinder and inlet valve at the lower end of the cylinder are closed.

40 On the succeeding upward stroke of the piston, the exhaust valve at the lower end of the cylinder closes and the corresponding inlet valve opens, thereby permitting a charge of explosive vapor to be drawn into the lower portion of chamber 11 and simultaneously the charge of explosive vapor drawn into the upper portion of said chamber is compressed therein by reason of the fact that the piston is moving upwardly in 45 the chamber and both exhaust and inlet valves at the upper end of the cylinder are closed. This stroke of the piston is graphically illustrated by diagram B, Fig. 2.

When the piston reaches the upper end of 50 its combined compression and suction stroke, as just described, a spark is produced between the points of the spark plug at the upper end of the cylinder, with the result that the piston is moved downward on its 55 combined power and compression stroke

with the result that the explosive charge drawn into the lower portion of the chamber 11 will be compressed. During this stroke, the inlet and exhaust valves at both ends of the cylinder are closed as illustrated 70 in diagram C, Fig. 2.

When the piston reaches its lower limit of movement on the combined power and compression stroke as just described, a spark is produced between the points of the spark 75 plug in the lower end of the cylinder, with the result that the piston is driven upwardly on its combined power and exhaust stroke, during which time the exhaust valve at the upper end of the cylinder is open, thereby 80 permitting the burnt gases to be discharged from the upper portion of chamber 11. During this stroke, the inlet valve at the upper end of the cylinder and both inlet and exhaust valves at the lower end of the cylinder 85 are closed as graphically illustrated by diagram D, Fig. 2.

The space between the cylinders is closed by plates such as X, thus forming an in- 90 closed chamber in which the pitman or connecting rod 15 operates.

The crank case 17 is preferably filled or partially filled with lubricating oil and as the crank revolves in said case, a portion of said oil will be carried upward through 95 opening 20 and will be thrown from the pitman or connecting rod 15 through the openings 14, with the result that the inner faces of the walls of the chambers 11 and the external faces of the pistons 12 will be effectively lubricated.

It will be noted that each manifold is provided with a passageway for the explosive mixture drawn into the engine cylinders and likewise with a passageway for the discharge of the burnt gases, and by virtue of this construction each manifold is heated to a considerable degree by the exhaust passing therethrough, with the result that the explosive vapor will be pre-heated to a considerable extent before it passes into the combustion chamber within the cylinder.

It will be understood that a multi-cylinder engine can be constructed in accordance with my invention, and where such construction is employed, it is only necessary to duplicate or multiply the construction herein illustrated and described.

An engine of my improved construction is comparatively simple, is efficient to a 120 comparatively high degree and owing to its compactness, is particularly adaptable for use in motor vehicles, power boats, and the like.

It will be readily understood that minor 125 changes in the size, form and construction of the various parts of my improved engine can be made and substituted for those herein shown and described, without departing from the spirit of my invention, 130

the scope of which is set forth in the appended claims.

I claim:

1. In an internal combustion engine, a pair of cylinders arranged side by side, there being vertically disposed openings formed in the adjacent walls of said cylinders, a plate applied to the upper ends of the cylinders for closing the combustion chambers therein, a crank case applied to the lower ends of the cylinders, a portion of which crank case constitutes a plate to close the lower ends of the combustion chambers in said cylinders, there being an opening in said plate between the cylinders, a double-headed piston arranged for operation within each cylinder, a shaft connecting the central portions of the piston, which shaft passes through the slots in the walls of the cylinders, a pitman journaled on the central portion of said shaft, which pitman passes through the opening in the top of the crank case, a crank shaft arranged for operation within the crank case to which shaft the lower end of the pitman is connected, plates secured to the cylinders for closing the space in which the pitman operates, inlet and exhaust valves arranged at both ends of both cylinders for controlling the inlet of explosive vapor into the ends of each combustion chamber and for controlling the discharge of burnt gases from said chamber, housings fixed to the engine cylinders, valve stems carried by the inlet and exhaust valves, which stems extend into the housings, a cam shaft journaled in said housings, cams on said shaft within the housings, which cams engage the inner ends of the valve stems, and a driving connection from the crank shaft to said cam shaft.
2. In an internal combustion engine, a pair of cylinders arranged side by side, there being vertically disposed openings formed in the adjacent walls of said cylinders, a plate applied to the upper ends of the cylinders for closing the combustion chambers therein, a crank case applied to the lower ends of the cylinders, a portion of which crank case constitutes a plate to close the lower ends of the combustion chambers in said cylinders, there being an opening in said plate between the cylinders, a double-headed piston arranged for operation within each cylinder, a shaft connecting the central portions of the piston, which shaft passes through the slots in the walls of the cylinders, a pitman journaled on the central portion of said shaft, which pitman passes through the opening in the top of the crank case, a crank shaft arranged for operation within the crank case to which shaft the lower end of the pitman is connected, plates secured to the cylinders for closing the space in which the pitman operates, inlet and exhaust valves arranged at both ends of both cylinders for controlling the inlet of explosive vapor into the ends of each combustion chamber and for controlling the discharge of burnt gases from said chamber, housings fixed to the engine cylinders, valve stems carried by the inlet and exhaust valves, which stems extend into the housings, a cam shaft journaled in said housings, cams on said shaft within the housings, which cams engage the inner ends of the valve stems, and a driving connection from the crank shaft to said cam shaft.

In testimony whereof I hereunto affix my signature in the presence of two witnesses, this 21st day of November, 1916.

MARION M. McCOY.

Witnesses:

M. P. SMITH,
M. A. HANDEL.
